V. R. DESPARD

HUSK OR SOCKET HOUSING

Filed March 7, 1924

2 Sheets-Sheet 1

Fig. 1.

Inventor
Victor R. Despard.

By: May H. Zabel Atty.

UNITED STATES PATENT OFFICE.

VICTOR R. DESPARD, OF VALPARAISO, INDIANA, ASSIGNOR TO MCGILL MANUFACTURING COMPANY, OF VALPARAISO, INDIANA, A CORPORATION OF INDIANA.

HUSK OR SOCKET HOUSING.

Application filed March 7, 1924. Serial No. 697,680.

My invention relates to electrical fixtures and more particularly to a casing or husk for a switch mechanism.

It is a purpose of my invention to provide an enclosure for a switch mechanism that is provided with an opening in the side wall thereof through which the conductors may be led into the fixture and an opening in one end thereof through which a switch operating mechanism extends, said switch operating mechanism preferably comprising an operating member extending endwise beyond said enclosure. The enclosure is preferably in the form of a husk of porcelain or other insulating material, although this may not always be the case.

The switch mechanism may be of any kind and may be mounted in any suitable manner. In referring to switch mechanism in this specification I am not referring merely to the switching means comprising the contact members, but the entire mounting for the switch mechanism. It is a further purpose of my invention to provide co-operating means on the switch mechanism within the enclosure and said enclosure for preventing relative rotational movement of the switch mechanism in the enclosure.

It is still a further purpose of the invention to provide suitable means for securing the electrical fixture, comprising the enclosure member, to a suitable tubular member or conduit, such as is usually used in fixtures of this character, the said enclosure member being secured to the tubular member at the side wall portion thereof. Said means preferably comprises an angular bracket which is secured to the end wall portion of the enclosure or casing and which is provided with a suitable opening through which the conductors leading from the tubular member may pass which is substantially aligned with the side opening in said enclosure member. Preferably, the enclosure member is provided with a recess in the end wall thereof for receiving a portion of this bracket and with a groove leading from said recess to the opening in the side wall thereof to receive the portion of the bracket extending from the end of said member to the opening in the side wall thereof.

It is still another purpose of the invention to provide a device of the above mentioned character with an internal shoulder for re-

ceiving the switch mechanism thereagainst and to provide means extending through the end wall of said housing or enclosure member having clamping means co-operating therewith to clamp said switch mechanism in position in said enclosure member and against said shoulder.

It is another important purpose of the invention to provide a device of the above mentioned character that is particularly adapted to be placed in position either with the lamp receiving socket member extending upwardly from the switch mechanism or depending therefrom, the switch operating means being of such a nature that the efficiency thereof will be as great in one position as in another and the appearance of the entire device will be as pleasing in one position thereof as in another.

Other objects and advantages of the invention will appear as the description of the accompanying drawings proceeds. However, I desire to have it distinctly understood that I do not intend to limit myself to the exact details shown or described but that I intend to include as part of my invention all such obvious changes and modifications of parts as would occur to a person skilled in this art and as would fall within the scope of the claims.

In the drawings:

Fig. 1 is a view partly in section and partly in elevation of my improved electrical fixture, showing the same used in connection with a wall bracket member, the electrical fixture being shown in full lines in an up-standing position and in dotted lines in a depending position;

Fig. 2 is a vertical sectional view of the enclosure member and parts mounted thereon, showing the member carrying the switch mechanism in elevation;

Fig. 3 is a bottom plan view of the device shown in Fig. 2, showing one end of the enclosure member or housing;

Fig. 4 is a fragmentary elevational view of the housing or enclosure member detached, taken from substantially the line 4—4 of Fig. 2, the bracket member and other parts attached thereto being omitted in Fig. 4; and

Fig. 5 is a fragmentary sectional view taken on the line 5—5 of Fig. 2.

Referring in detail to the drawings, in Fig. 1 is shown a wall bracket member having

a conduit 10 provided with a threaded end portion 11 which is screw-threadedly received in a suitable opening in the bracket member 12 secured to a suitable support 13, 5 such as a wall, in any suitable manner. The member 10 may be of any desired material but is ordinarily of nickel plated tubing where the device is used as a bathroom fixture to harmonize with the other bathroom 10 fixtures. An enclosure member or bell 14 is provided which is clamped against the wall by means of the flanged sleeve 15 which is held in position by the set screw 16 in the usual manner. The member 14 is preferably 15 of porcelain when the device is used for a bathroom fixture. The outer end of the tube or conduit 10 is threaded as indicated at 17 which is adapted to receive the internally screwthreaded nipple 18 provided on 20 the bracket member 19 which is secured to the end portion 20 of the housing or switch mechanism enclosure 21 by means of the screws 22.

The housing 21 is provided with a longitudinal bore 23 for receiving the member carrying the switch mechanism. The switch mechanism is preferably supported upon a pair of suitable insulators 24 which together form an insulating housing for the switch 30 mechanism. The screw shell terminal 25 is mounted in any suitable manner on said members 24 and is suitably connected with the switch mechanism. The member 21 is provided with a passage or bore 26 extending from the end 20 thereof to the bore 23 and forming an internal shoulder 27 against which the members 24 are adapted to be clamped, the clamping being accomplished by means of the screwthreaded nut or clamping 35 member 28 that screwthreadedly engages with the screwthreaded nipple 29 extending from the switch mechanism through the opening 26. The member 29 also serves as a housing for the switch operating member 40 which is preferably actuated by means of the lever 30, the lever 30 being shown in Fig. 1 in its normal position and in Fig. 2 in the position which it assumes when the switch is actuated. A fibre washer 31 is 45 preferably interposed between the nut or clamping member 28 and the bracket 19.

The member 21 may be made of any suitable material but is preferably made of porcelain or some other insulating material 55 although this is not absolutely necessary. In the case of a bathroom fixture it is preferably of porcelain to conform with the member 14 and with the other bathroom fixtures. The member 21 is further provided with an 60 opening in the side wall thereof, said opening being indicated by the numeral 32, and is further provided with a recess 33 surrounding the opening 26 at the end 20 thereof for receiving the substantially circular portion 34 of the member 19. A groove is 65

also provided at 35 which leads from the recess 33 to the opening 32 and receives the portion of the bracket 19 leading from the circular end 34 to the upstanding portion 36 thereof to which the member 18 is secured 70 in any suitable manner as by means of the upset annular flange portion 37 extending through the opening 38 in the portion 36. Thus, the member 19 is concealed from view in the groove and recesses referred to.

After the member 18 is screwed into position on the tubing 10, the same is secured in this position thereon by means of a set screw 39. The conductors 40, leading to the switch mechanism, extend from the conduit or tube 10 through the opening 41 in the member 18 and through the opening 32 to the switch mechanism. The housing or enclosure member 21 is also provided with a recess 42 surrounding a portion of the opening 32 for receiving the members 36 and 18. Thus, the only portions of the device that project beyond the contour of the member 21 are the member 10 and the member 18 at the side thereof, the nut 28 and the operating lever 30 at one end thereof and the bulb or lamp 43 at the other end thereof, thus making a very neat and attractive fixture.

It will be seen from Fig. 1 that with the lever operated switch mechanism with the lever arranged substantially in axial alignment with the screw shell terminal 25, the fixture can be arranged either in the full line or dotted line position shown in Fig. 1 without in any way detracting from the appearance thereof or without in any way affecting the efficiency of the switch operating mechanism.

In order to prevent relative rotation between the switch mechanism as a whole and the housing or enclosure member 21, a projection 44 is provided on the member 21 which is adapted to seat in a suitable recess 45 provided between the members 24. Thus, the arrangement of the recess and projection will hold the parts against rotation and hold the opening through which the conductors 40 pass from the switch mechanism in substantial alignment with the opening 32 and the conduit or tubing 10, thus preventing any possible damage to the wires by any twisting of the socket when the lamp 43 is inserted. The entire switch mechanism is firmly clamped in position in the housing 21 by means of the nut 28 and, due to the construction of the bracket 19 and the corresponding construction of the housing or enclosure member 21, there can be no relative rotation of the housing and bracket, the bracket being substantially held in fixed position by means of the screws 22 when the member 34 is seated in the recess 33 due to the fact that the other parts of the bracket are mounted in the groove 35 and the recess 42.

Having thus described my invention, what I desire to claim and secure by United States Letters Patent is:

1. In a device of the character described, 5 switch mechanism and an enclosure member for said switch mechanism having a longitudinal bore open at one end thereof, a reduced bore extending to the opposite end of said member and communicating with 10 said longitudinal bore and an opening extending through the side wall of said member and communicating with said longitudinal bore, the outer surface of said member being recessed around said reduced 15 bore.
2. In a device of the character described, 5 switch mechanism and an enclosure member for said switch mechanism having a longitudinal bore open at one end thereof, a reduced bore extending to the opposite end 20 of said member and communicating with said longitudinal bore and an opening extending through the side wall of said member and communicating with said longitudinal bore, the outer surface of said member being recessed around said reduced 25 bore, said recess extending to said side opening.
3. In a device of the character described, 30 switch mechanism, an enclosure member therefor having a recess in the side and end thereof and an angular bracket secured to one end of said member and extending around the side thereof said bracket being mounted in said recess.
4. In a device of the character described, 35 switch mechanism, an enclosure member therefor having openings in the side wall and end wall thereof, an angular bracket secured to one end of said member and extending around the side of said member, said bracket having openings therein aligning with the openings in said enclosure member and means extending through said end opening for securing said mechanism in position.
5. In a lighting fixture, switch mechanism, an enclosure member of insulating material therefor having a recess in one end thereof, an opening in the side thereof and a groove connecting said recess with said opening, and a bracket secured to said member and mounted in said recess and extending over said opening.
6. In a lighting fixture, switch mechanism, an enclosure member of insulating material therefor having a recess in one end thereof, an opening in the side thereof and a groove connecting said recess with said opening, and a bracket secured to said member and mounted in said recess and extending over said opening, said bracket resting in said groove.
7. A lamp bracket having a hollow body portion, means for supporting said body por- 55 tion having provision for leading conductors toward the interior of said body portion, a lamp socket and switch carrying framework insertable into said body portion at one end thereof, means secured to said framework 70 and extending through the opposite end of said body portion and accessible from the exterior thereof for detachably securing said lamp socket and switch carrying framework in said body portion and switch mechanism 75 operating means extending through said body portion at said last mentioned end thereof substantially on the axis of the lamp socket.
8. A lamp bracket having a hollow body portion, means for supporting said body portion having provision for leading conductors toward the interior of said body portion, a lamp socket and switch carrying framework insertable into said body portion at one end 80 thereof, means secured to said framework and extending through the opposite end of said body portion and accessible from the exterior thereof for detachably securing said lamp socket and switch carrying framework 85 in said body portion, switch mechanism operating means extending through said body portion at said last mentioned end thereof substantially on the axis of the lamp socket, and cooperating means on said lamp socket 90 and switch mechanism and said body portion to hold said lamp socket and switch mechanism against rotation in said body portion.
9. A wall bracket for an electric lamp 100 comprising a hollow enclosing casing, means for supporting said casing having provision for enclosing lead-in conductors extending toward the interior of said casing, said casing having an opening in one end thereof, a lamp socket and switch mechanism carrying framework insertable as a unit into said casing through said opening so that the outer extremity of said lamp socket is substantially flush with the face of said casing at said 105 opening, means projecting from said framework through said casing and exteriorly operable for detachably securing said unit in said casing, and means for operating said switch mechanism extending through the 110 other end of said casing.
10. A wall bracket for an electric lamp comprising a hollow enclosing casing, means for supporting said casing having provision for enclosing lead-in conductors extending 120 toward the interior of said casing, said casing having an opening in one end thereof, a lamp socket and switch mechanism carrying framework insertable as a unit into said casing through said opening so that the outer extremity of said lamp socket is substantially flush with the face of said casing at said opening, means projecting from said framework through said casing and exteriorly operable at the other end of said casing 125 130

for detachably securing said unit in said casing, and means for operating said switch mechanism extending through the said other end of said casing.

- 5 11. A lamp bracket having a hollow body portion, means for supporting said body portion having provision for leading conductors toward the interior of said body portion, a lamp socket and switch carrying frame-
10 work insertable into said body portion as a unit, a securing member projecting end-
wise from said framework through said body portion, means exteriorly operable for de-
tachably securing said member to said body
15 portion and switch mechanism operating means extending through said body portion.
12. In a device of the character described, a switch mechanism carrying framework, an

enclosure member for said framework having a longitudinal bore open at one end thereof, a reduced bore extending through the opposite end of said member and communicating with said longitudinal bore to provide a shoulder in said member and an opening extending through the side wall of said member and communicating with said longitudinal bore, means on said framework projecting through said reduced bore for detachably clamping said framework to said shoulder, and means extending through said last named means and said reduced bore for controlling the switch mechanism.

In witness whereof, I hereunto subscribe my name this 14th day of February A. D., 1924.

VICTOR R. DESPARD.
